UNITED STATES PATENT OFFICE.

JOHN DEAM KNEEDLER, OF SIOUX CITY, IOWA, ASSIGNOR OF ONE-HALF TO
JAMES HENRY BALL, OF OAKLAND, NEBRASKA.

COIN-OPERATED MECHANISM.

SPECIFICATION forming part of Letters Patent No. 606,463, dated June 28, 1898.

Application filed March 29, 1897. Serial No. 629,703. (No model.)

To all whom it may concern:

Be it known that I, JOHN DEAM KNEEDLER, a citizen of the United States, residing at Sioux City, in the county of Woodbury and State of Iowa, have invented certain new and useful Improvements in Coin-Operated Mechanisms; and I do hereby declare the following to be a full, clear, and exact description of the invention, such as will enable others skilled in the art to which it appertains to make and use the same.

The object of this invention is to provide a coin-operated machine in which the insertion of the coin will form a connection between certain operating-levers by which they may be manipulated to move a carriage one step or predetermined distance to bring a section thereof in line with the delivery-chute.

With the above object in view the invention consists in the particular construction of the operating-levers and manner of connecting the same by a coin or nickel, together with a carriage moved through the intervention of the levers when operated in unison.

The invention further consists in the particular construction of the carriage or case, which contains the material to be delivered at the proper operation of the coin-controlled mechanism.

The invention further consists in the particular construction and organization of the several parts, all as will be hereinafter fully set forth, and specifically pointed out in the claims.

In the accompanying drawings, forming part of this specification, Figure 1 is a front elevation of a coin-operated machine constructed in accordance with my invention. Fig. 2 is a vertical sectional view. Fig. 3 is a sectional view on the line 3-3 of Fig. 2. Fig. 4 is a sectional view on the line 4-4 of Fig. 2.

The mechanism of my improved coin-controlled apparatus is inclosed within a suitable casing, the front of which may be made up to present any particular design. This inclosing case is divided by a horizontal partition 1 to present an upper compartment 2, in which moves a carriage 3, preferably provided with rollers 4 in order that it may be easily moved by the mechanism hereinafter

described. The carriage or case 3 is made up of side pieces *a* and *b*, connected by cross-wires 5, arranged in horizontal series. There are three or more horizontal series of cross-wires which are arranged with respect to each other, so as to provide vertical spaces or compartments to receive the materials or objects to be delivered by the operation of the mechanism. This case is primarily located at the rear end of the chamber or compartment 2 of the cabinet, and directly in front of the same the floor or horizontal partition 1 is provided with a transverse slot 6, which opens into the lower part of the cabinet, the forward end of which is opened, so that the material which is deposited on the bottom 7 thereof can be readily removed.

The lower series of transverse wires 5 of the carriage or case which contains the material are extended beyond the side piece *b* to provide projections 8, with which the coin-controlled mechanism engages.

From the under side of the floor or horizontal partition 1 and in front of the vertical slot 6 therein depends a hanger 9, which forms a bearing for a lever 10, the rear end of which is bent upward to extend through a slot 11 in the floor and receive a pawl 12, pivoted thereto. The free end of this pawl is adapted to engage the projections 8 of the carriage and is actuated into such engagement by a flat spring 13, attached to the said floor and bearing against the under side of the outer end of the pawl. The head of the pawl 12 is curved, as shown, so that it will pass under or escape the projections when the said pawl is moved rearward. The forward end of the lever 12 is curved downward and enters a slot in a vertical tube 14, which forms the coin-chute, and adjoining this end the lever has attached thereto a helical spring 15, rigidly attached at its other end to the floor 1 and operating to hold said lever normally in horizontal position, as indicated in Fig. 2. The coin-chute extends from the inlet-opening *c* thereof downward through the compartment 2 of the cabinet to position the lower end thereof on a line with the lever 10, hereinbefore described, the direction which the coin-chute takes being indicated in dotted lines in Fig. 1.

Pivoted within the front board of the cabinet is a second lever 16, the inner end of which is curved to correspond with the adjoining end of the lever 10 and lies partially within the lower end of the coin-chute, the said inner end being normally depressed by a flat spring 17, bearing upon the upper edge of the same. The outer end of the lever 16 projects beyond the front of the cabinet and is formed into a grasping portion or knob 18. From the foregoing description, taken in connection with the accompanying drawings, the construction and operation of my improved coin-controlled apparatus will be readily apparent, for when a nickel is deposited into the coin-chute 14 it will fall and wedge itself between the adjoining curved ends of the levers 10 and 16 to so connect said levers that a depression of the outer end or knob 18 of the lever 16 will cause a rocking movement of the lever 10, and said movement will draw the pawl forward, and this will pull the carriage 3 forward a certain distance or sufficient to bring the material located in front of the first wires of the several series on a line with the discharge-opening 6, through which said material will fall to the bottom 7. After this operation the lever 16 is released, which will permit the coin to drop into the drawer or receptacle below, and as the lever 10 assumes its normal position through the operation of the spring 15 the pawl 12 will be moved rearward to engage the next projection or wire 8, and thus be in a position to move the carriage one step forward, when the mechanism is again properly manipulated.

It will be observed that the adjacent ends of the levers 10 and 16 are bent downward and curved or rounded, so that the point or their nearest approach to each other is below the plane of their pivots, and from said point of nearest approach the curvatures should be practically concentric with the pivots of the respective levers in order that operative connection may be maintained through the interposed coin until the carriage shall have moved forward the required distance.

In the drawings I have shown a transverse groove or pocket 19 in the rear of the delivery-opening 6 in the floor 1, and into this groove or pocket the material is moved prior to the carriage being operated to deliver the same.

This machine is designed more particularly for use in connection with hotels or other public places, and the spaces between the cross-wires are adapted to each receive a package containing paper and envelop and a stamp.

It will be understood, of course, that the machine or device could be adapted to receive other articles, the delivery-openings 6 and space between the cross-wires 5 being made larger or smaller to correspond.

Having thus described the invention, what is claimed as new is—

1. In a coin-controlled apparatus, the combination with a cabinet having a floor with a transverse opening therein, a carriage movable over said transverse opening and provided with a series of vertical spaces or compartments, together with levers operating the carriage through the intervention of a coin, one of the levers being spring-actuated and having a pawl to engage a series of projections on the carriage corresponding in number with the spaces or compartments therein, substantially as shown and set forth. 75

2. In a coin-controlled apparatus, the combination with a cabinet having a floor with a transverse opening 6, of a carriage movable upon the floor over said transverse opening and provided with a series of vertical spaces or compartments, lugs or projections extending from said carriage, and levers adapted to operate or move the carriage when a coin is interposed between the adjoining ends of the same, one of the levers having a pawl which engages the projections of said carriage, substantially as shown and for the purpose set forth. 80

3. In a coin-controlled apparatus, the combination with a cabinet having a floor with a transverse opening, of a carriage or case movable on said floor over the transverse opening and provided with projections, a lever pivoted within the cabinet and provided with a pawl in engagement with said projections, a second lever having its inner end adjoining the end of the aforesaid lever, and a tube or coin-chute leading to the space between the adjoining ends of the levers, substantially as shown and for the purpose set forth. 90

4. In a coin-controlled apparatus, the combination with the floor having a transverse opening therein, of a carriage movable upon the floor over said transverse opening and provided with a series of vertical spaces or compartments, projections on said carriage corresponding in number with the vertical spaces or compartments, a lever centrally fulcrumed and provided at its rear end with a pawl in engagement with said projections and at its other end with a curved depending portion, a second lever pivoted in the cabinet and having its inner end curved downward and located adjoining the corresponding end of the other lever, and a coin-chute leading to the space between said levers, substantially as shown and for the purpose set forth. 105

5. In a coin-controlled apparatus, the combination with the cabinet having a floor with a transverse opening therein, of a carriage located upon the floor and having a series of vertical spaces or compartments and projections corresponding in number therewith, a lever 10 centrally fulcrumed and provided with a pawl, spring-actuated to engage the projections on the carriage, a spring for lifting the forward end of said lever, a second lever piv- 115 120 125

oted in the cabinet and having a spring for depressing the inner end thereof, the adjoining ends of the said levers being curved as shown, and a coin chute or tube leading to the space between the adjoining ends of the levers, substantially as shown and for the purpose set forth.

In testimony whereof I have signed this specification in the presence of two subscribing witnesses.

JOHN DEAM KNEEDLER.
